LLP

(57) **CLAIM**

The ornamental design for a wheel, as shown and described.

DESCRIPTION

FIG. 1 is a perspective view of a wheel showing my new design;

FIG. 2 is a front elevational view thereof; and,

FIG. 3 is a cross-sectional view thereof taken along the line 3—3 in FIG. 2.

The broken line disclosure in FIGS. 1-3 is for illustrative purposes only and forms no part of the claimed design.
The rear of the wheel forms no part of the claimed design.

1 Claim, 2 Drawing Sheets

FIG. 1
